UNITED STATES PATENT OFFICE

ELMER J. KISSICK, OF DORMONT, PENNSYLVANIA

STOPPER

Application filed August 4, 1932. Serial No. 627,488.

The present invention relates to a stopper designed for use on milk bottles and the like and has for its prime object to provide a very simple device of this nature formed of only four parts and capable of being easily manipulated in opening and closing the stopper for the purpose of dispensing the contents of the bottle.

Another very important object of the invention resides in the provision of a stopper of this nature which is highly sanitary because it is easily cleaned and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

In the drawings:

Figure 1 is a side elevation of a stopper embodying the features of my invention showing the same in the neck of a bottle which is shown in section.

Figure 2 is a similar view showing the parts in a pouring position.

Figure 3 is a top plan view of a stopper showing the valve placed in one position.

Figure 4 is a similar view showing the plate in another position.

Figure 5 is a sectional view taken on the line 5—5 of Figure 3.

Figure 6 is a sectional view taken on the line 6—6 of Figure 4.

Figure 7 is a perspective view of the valve plate, and

Figure 8 is a detail section taken on the line 8—8 of Figure 1.

Referring to the drawings in detail it will be seen that numeral 1 denotes a plug or body of the stopper shaped to conform to the opening in the neck of the bottle in which it is to be used. This plug is provided with a central bore 2 enlarged or countersunk at its bottom end as indicated at 3. A bolt 4 is receivable in the bore 2 with its head countersunk in the end 3 and the threaded end of the bolt projecting a dis-

tance above the upper surface of the plug. The plug is provided with an off center vent bore 5 and an offcenter pouring bore 6. Numeral 7 denotes a rectangular plate with a square opening 8 in the center thereof. Numeral 9 denotes a knob having a squared end 10 fitted in the opening 8. It will be noted that both the opening and the end are tapered as illustrated in Figure 6.

The bolt 4 is threaded in the knob 9 to hold the plate 7 in sliding abutment with the top surface of the plug so that by turning the knob the plate may be placed in the closed position shown in Figure 3 or in the open position shown in Figure 4.

It is thought that the construction, utility and advantages of this invention will be quite apparent without a more detailed description thereof.

It is apparent that changes in details of construction may be resorted to without departing from the spirit or scope of the invention as hereinafter claimed or sacrificing any of its advantages.

Having thus described my invention, what I claim as new is:

A stopper including a plug having a central bore, an off center vent bore, and an off center pouring bore, a bolt extending through the center bore, an oblong plate having a non-circular opening, walls of which flare upwardly and outwardly, and a knob having a non-circular end to fit in the opening, the walls of said non-circular end sloping upwardly and outwardly to engage the flaring walls of the opening in the plate, said bolt being threadedly engaged in said knob.

In testimony whereof I affix my signature.

ELMER J. KISSICK.
